ALPHABET FOR MONOGRAMS OR THE LIKE

George Berlant, Bellerose, N.Y., assignor to New Hermes
Engraving Corporation, New York, N.Y.

Filed Nov. 12, 1969, Ser. No. 20,033

Term of patent 14 years

Int. Cl. D18—04

U.S. Cl. D64—16

FIG. 2

FIG. 1 is a face view of an alphabet for monograms or the like showing my new design;

FIG. 2 is a face view of another embodiment thereof wherein double rather than triple lines are employed.

I claim:

The ornamental design for an alphabet for monograms or the like, substantially as shown and described.
